DESIGN FOR A RING

Henry Pommier, New York, N. Y.

Application January 25, 1945, Serial No. 117,568

Term of patent 3½ years

(Cl. D45—10)

To all whom it may concern:

Be it known that I, Henry Pommier, a citizen of the United States of America, residing in New York, county of New York and State of New York, have invented a new, original, and ornamental Design for a Ring, of which the following is a specification, reference being had to the accompanying drawing, forming part thereof.

Fig. 1 is a perspective view of a ring showing my new design.

Fig. 2 is a top plan view thereof.

I claim:

The ornamental design for a ring, substantially as shown.

HENRY POMMIER.
